UNITED STATES PATENT OFFICE

2,616,769

ELEVATING LADDER SCAFFOLD

Nelson H. Rector, Atlanta, Ga.

Application December 29, 1947, Serial No. 794,285

2 Claims. (Cl. 304—31)

1

The present invention relates to a scaffold device, and more particularly to a scaffold structure in combination with a pair of rolling ladders adapted to be moved along the side of a building.

The primary object of the present invention is to provide an adjustable scaffold structure including a platform supported by two ladders adapted to roll along the side of a building and which additionally furnish means of leaving or entering the building in the event of an emergency, such as fire.

Another object is to provide a scaffold which is quickly and easily adjustable either upwardly or downwardly.

A further object is to provide a scaffold device with a simple and effective means to automatically lock the scaffold against downward movement, preferably in combination with means to release said lock means to permit selective downward movement of the scaffold.

In one of its aspects, the present invention embraces an adjustable scaffold device for use with a pair of ladders provided with rungs, with said device including a platform provided with a slot at each end portion extending lengthwise of the platform to vertically receive a ladder, with a brace for each ladder secured to said platform at said slots therein, with said brace being adapted to slidably engage over a ladder, a pair of lock rods for each ladder, with said lock rods being pivotally secured to the underside of said platform and adapted to have the inner end portions thereof fit over a suitable rung in the ladder and a stop block for each lock rod secured to the underside of said platform and bearing against said rod when the scaffold device is in locked position.

Other and further objects and advantages of the present invention will be apparent from the following description thereof and from the claims appended thereto.

In the drawing wherein like numerals refer to like or corresponding parts throughout the several views:

Figure 1 is a fragmentary front elevation of a building showing the scaffold device disposed on a pair of rolling ladders, and embodying the features of the present invention;

Figure 2 is a fragmentary sectional view taken substantially along the line 2—2 of Figure 1, in the direction of the arrows;

Figure 3 is a sectional view taken along the line 3—3 of Figure 2, in the direction of the arrows;

Figure 4 is a sectional view taken along the line 4—4 of Figure 2, in the direction of the arrows;

Figure 5 is an enlarged fragmentary detail showing means for automatically locking a ladder against downward vertical movement, and means to release said locking means; and

Figure 6 is a detail showing the spring-operated

2

plunger for disengaging the means for locking the scaffold device against downward movement.

Referring now to the drawing, the numeral 10 generally represents a building, such as an apartment house, hotel, hospital, office building, asylum, or similar building, upon which is mounted a rolling ladder assembly, as more fully set forth in my copending patent application, Serial No. 743,645, filed April 24, 1947. The rolling ladder assembly generally includes a track 11 disposed around the top portion of the building 10, with a wheel assembly 12 and 13 adapted to roll upon the track 11, with ladders 14 and 15 respectively secured to said wheel assemblies 12 and 13 in any suitable manner, so that ladders 14 and 15 may roll as a unit along the track 11.

The present invention concerns itself with a scaffold device, preferably used in combination with a pair of rolling ladders 14 and 15, and generally comprises a platform 16 which is provided with slots 17 and 18 at opposite end portions of the platform 16, with said slots 17 and 18 extending lengthwise of said platform 16. Ladders 14 and 15 are adapted to fit into slots 17 and 18 respectively, so that the platform 16 is free to move upwardly or downwardly along the length of said ladders 14 and 15.

The structure of the present scaffold device is identical with relation to ladders 14 and 15 and, therefore, the description will be made only as to one. The ladder 15 has the usual rungs 19 extending throughout the vertical length of said ladder. A brace member generally represented by the numeral 20 is mounted on the upper side of platform 16 and is secured thereto by means of bolts 21, or the like. Said brace 20 generally includes a substantially inverted U-shaped bracket fastened to the central portion of an apertured bar 22, which fits over the ladder 15, and is moved upwardly or downwardly with the platform 16. The brace 20 is of importance to keep the platform 16 level when it is in use, that is to say, to prevent it from tipping if weight is shifted to the outer edges thereof.

On the underside of the platform 16, there is mounted means for automatically locking the scaffold device against downward movement, with said locking means leaving the platform free to be moved upwardly. Said locking means generally include a pair of lock rods 23 and 24 which are pivoted to the underside of platform 16. The rod 23 is secured to a rotatable shaft 25 which extends substantially throughout the length of platform 16 on the underside thereof being supported by means of roll bearings 28, which are secured to the platform 16.

The shaft 25 is connected to the lock rod 23 and to the lock rod which corresponds to lock rod 23 in the other pair of lock rods which operate in connection with rolling ladder 14. Likewise, the lock rod 24 is connected to shaft 27 so that when shaft 27 is rotated throughout a limited

degree, lock rod 24 and its corresponding lock rod are moved together simultaneously.

To operate the shafts 25 and 27, and the lock rods 23 and 24, there is provided a plunger 29 which extends above the platform 16, and is disposed near the rolling ladder 15. The plunger 29 is provided with a spring 30 so that when the plunger 29 is depressed, the spring will automatically move it back into a raised position. The plunger 29 generally includes an elongated rack bar 31 which fits through a suitable opening in the platform 16 with said rack bar 31 being provided with teeth engaging the teeth of a pair of swingable elements 32 and 33, which elements 32 and 33 are respectively secured to the shafts 25 and 27, so that a depression of the plunger 29 will cause the element 32 to swing in one direction, and element 33 to swing in the opposite direction, to thereby rotate shafts 25 and 27 in opposite directions and to swing lock rods 23 and 24 away from a rung in the ladder, when said scaffold device is so positioned that the lock rods 23 and 24 are disposed between rungs in the ladder.

The lock rods 23 and 24 are each provided with a counterweight 23a and 24a at the outer end portions thereof, which counterweights 23a and 24a cause the lock rods 23 and 24 to automatically swing into engagement over the rungs of the ladders, as the scaffold platform is moved upwardly. As the lock rods 23 and 24 engage over the rung of the ladder, a slight lowering of the platform 16 will cause the rods 23 and 24 to engage stop blocks 23b and 24b secured to the underside of the platform 16 by means of bolts 23c and 24c.

The scaffold device is provided with the conventional block and tackle structure generally indicated by the numeral 34 with reference to ladder 15, and 35 with reference to ladder 14. The block and tackle structure includes the usual pulley arrangement, having the free lines 36 and 37 for raising and lowering the platform 16. It is to be noted that the upper portion of the block and tackle arrangement is secured to the upper rung of the ladders 14 and 15, so that the platform 16 and the rolling ladders 14 and 15 may be moved along the side of the building as a unit. The block and tackle structure forms no part of the present invention per se, and therefore it has not been described in detail.

In operation, the scaffold device may be raised by means of the ropes 36 and 37 to any desired height on the ladders 14 and 15. When the proper position is reached, the lock rods 23 and 24, in each pair, fall over an appropriate rung in the ladder and upon a slight lowering of the platform 16, the lock rods 23 and 24 bear against the stop blocks 23b and 24b respectively, to thereby lock the platform 16 against downward movement. Thus it can be seen that I have provided automatic means for locking the platform 16 against downward movement. When it is desired to move the platform 16 downwardly, and to release the lock rods 23 and 24 from locked position, it is only necessary to move the platform 16 to a position between rungs on the ladders 14 and 15, by means of pulley ropes 36 and 37.

With the lock rods 23 and 24 in a position intermediate to rungs of the ladder, the operator then depresses the plunger 29 to operate shafts 25 and 27, and to swing lock rods 23 and 24 away from the rungs of the ladders, so that the platform 16 may be moved downwardly by means

of the block and tackle arrangement independent of the automatic locking means.

It is to be understood that my invention includes an adjustable scaffold device for use with a pair of ladders with means for automatically locking the scaffold device against downward movement, and preferably in combination with means to release said automatic locking means aforesaid so that the scaffold device may be selectively lowered through the operation of a conventional block and tackle arrangement.

Various modifications of the present invention will be apparent to those skilled in the art without departing from the spirit thereof, and it is therefore desired to be limited only by the scope of the appended claims.

What I claim is:

1. An adjustable scaffold device comprising a pair of spaced apart rolling ladders each provided with rungs, a platform provided with a slot at each end portion thereof extending lengthwise of the platform, a ladder vertically disposed in each of said slots, a pair of lock rods for each ladder adapted to engage the rungs 20 of the ladder to limit downward movement of said platform, said locks being pivotally secured to the underside of said platform and having a portion thereof fit over a suitable rung in said ladder, the axes of said lock rod pivots being substantially parallel to said rungs, said lock rods extending substantially perpendicularly to their pivotal axes in a direction toward said rungs and each having a portion extending beyond the rungs, means operated from said platform to simultaneously swing the lock rods in both pairs thereof away from a rung in each ladder, and said last mentioned means including a plunger provided with a rack having teeth adapted to engage the teeth of two rotatable elements each connected to a shaft secured to the corresponding lock rod in each of said pairs.

2. An adjustable scaffold device comprising, a pair of spaced apart rolling ladders each provided with rungs, a platform provided with a slot at each end portion thereof extending lengthwise of the platform, a ladder vertically disposed in each of said slots, a pair of oppositely disposed lock rods for each ladder, each of said lock rods being pivotally secured to the underside of said platform at opposite sides thereof and extending towards each other so that their free end portions overlap and have their under surfaces engaging over a suitable rung in a ladder, each of said lock rods being weighted at its opposite end, and a stop block for each of said lock rods secured to the underside of said platform and bearing against the upper surface of said rod when the scaffold device is in locked position.
